UNITED STATES PATENT OFFICE

THEODORE SUNDIN, OF NEW YORK, N. Y., ASSIGNOR TO SAGAMOR METAL GOODS CORPORATION, OF NEW YORK, N. Y., A CORPORATION OF NEW YORK

DESIGN FOR A VANITY BOX OR SIMILAR ARTICLE

Application filed March 6, 1933. Serial No. 47,401. Term of patent 3½ years.

To all whom it may concern:

Be it known that I, THEODORE SUNDIN, a citizen of the United States of America, and resident of Bronx, New York city, in the county of Bronx, State of New York, have invented a new, original, and ornamental Design for a Vanity Box or Similar Article, of which the following is a specification, reference being had to the accompanying drawing, forming part thereof.

In the drawing:

Fig. 1 is a plan view of a vanity box, or similar article showing my new design.

Fig. 2 is an edge view of the same.

I claim:

The ornamental design for a vanity box or similar article, substantially as shown.

THEODORE SUNDIN.
